(57) **CLAIM**

The ornamental design for a filter media retainer housing, as shown and described.

DESCRIPTION

FIG. 1 is a top perspective view of a filter media retainer housing in accordance with this invention.

FIG. 2 is a bottom perspective view of the filter media retainer housing of FIG. 1.

FIG. 3 is a front view of the filter media retainer housing of FIG. 1.

FIG. 4 is a right side view of the filter media retainer housing of FIG. 1.

FIG. 5 is a rear view of the filter media retainer housing of FIG. 1.

FIG. 6 is a left side view of the filter media retainer housing of FIG. 1.

FIG. 7 is a top view of the filter media retainer housing of FIG. 1; and,

FIG. 8 is a bottom view of the filter media retainer housing of FIG. 1.
